UNITED STATES PATENT OFFICE.

ARTHUR R. BARNETT, OF INDIANAPOLIS, INDIANA.

MEANS FOR ATTACHING AND REMOVING DETACHABLE BLADES AND THE LIKE.

1,261,680.

Specification of Letters Patent.

Patented Apr. 2, 1918.

Application filed November 20, 1916. Serial No. 132,471.

To all whom it may concern:

Be it known that I, ARTHUR R. BARNETT, a citizen of the United States, and a resident of Indianapolis, county of Marion, and 5 State of Indiana, have invented a certain new and useful Means for Attaching and Removing Detachable Blades and the like; and I do hereby declare that the following 10 of, reference being had to the accompanying drawings, in which like letters refer to like parts.

This invention relates to a means for attaching and removing detachable knife 15 blades or the like from a blade holder. It is used in connection with detachable blades which are secured and held in the blade holder by interlocking or frictional means so that it may be slidably attached and re- 20 moved therefrom.

The chief feature of the invention consists in means for holding the blade while the holder is being attached thereto or removed therefrom, and particularly a member hav- 25 ing a slot into which the knife blade is inserted and which has stops at each end there- of for engaging and holding the blade in place while the blade is being attached to or removed from the blade holder, especially 30 when such uniting or separating movement is longitudinal.

The full nature of the invention will be understood from the accompanying drawings and the following description and 35 claims.

In the drawings, Figure 1 is a central longitudinal section taken through the attaching and removing device, showing the knife blade and holder in dotted lines. Fig. 2 is 40 the same as Fig. 1, showing the blade partially removed from the holder. Fig. 3 is a cross section on the line 3—3 of Fig. 1. Fig. 4 is a plan view of the attaching and removing device. Fig. 5 is a central longitudinal section through a modified form. Fig. 6 is 45 an end view of Fig. 5. Fig. 7 is a plan view of the modified form. Fig. 8 is a side view of a modified form, adapted to be used for a curved blade and holder. Fig. 9 is an 50 end view of the modified form shown in Fig. 8.

In the drawings there is shown a device for attaching and removing a detachable knife blade 10 from a blade holder 11 which

together form a carving knife, butcher's 55 knife or the like. The blade is longitudinally removable from or attachable to said holder. For this purpose the holder has a longitudinal groove 111 to receive and hold the blade. 60

Secured to a base 12 by means of the screws 13, there is a projecting member 14 provided with a slot 15 into which said knife blade is insertible. One end of said projecting member is under-cut so as to receive one 65 end, preferably the point, of the blade for retaining it in position, substantially as shown. The other end of said member is adapted to engage the heel end of the blade, thereby acting as a stop and holding it while 70 the blade holder is being withdrawn longitudinally and rearwardly therefrom.

Figs. 5, 6 and 7 show a modified form having a block 112 provided with a longitudinal groove 114 into which the blade is 75 adapted to be inserted. The screws 20 are screwed into said block and secure it in position while being attached to or removed from the blade holder.

Figs. 8 and 9 show a second modified form 80 adapted to be used for curved blades, which is provided with a curved member 212 with a fibrous filler 213 and having outwardly extending longitudinal flanges 214 which are separated from each other and bolted in position by the bolts 220 which also act as stops to engage the ends of the removable blade 210 to engage or disengage it from the blade holder 211. 85

The operation of the device is as follows: 90 If it is desired to attach the knife blade to the blade holder, the blade is inserted in the slot so that it will be held therein. The holder is then placed in position to slide longitudinally and forwardly on said blade 95 until said blade is entirely inserted therein, when the holder and blade thus united may be lifted from the slot. By reversing the operation, the blade may be removed from the holder by inserting the blade in the slot 100 so that it is held therein at both ends, and withdrawing the holder longitudinally.

The invention, however, is not limited to the longitudinal movement of the blade holder, or the blade and holder may be 105 united or separated by movement otherwise than longitudinal. While a knife blade is herein shown, a blade with saw teeth or any

other edge may be similarly attached to and removed from a blade holder by the device herein shown.

The invention claimed is:

5. 1. Means for attaching and removing a detachable blade holder from the blade, comprising a sheet metal member having parts thereof arranged to form a longitudinal slot in the top thereof into which said blade 10 may be inserted, and a stop adjacent each end of the slot for engaging the ends of the blade to hold the same against longitudinal movement while the holder is being engaged with or disengaged from the blade, 15 said stops being under-cut for engagement with the pointed end of said blade.
2. Means for attaching and removing detachable knife blades or the like from a blade holder, comprising a sheet-metal member having parts thereof extended upwardly, 20 said upwardly extending portions having a slot in which the blade can be placed lengthwise thereof, one end of said slot being under-cut to engage the pointed end of said 25 blade and the other end provided with a stop whereby the blade will be held while said holder is longitudinally moved into or

withdrawn from holding engagement with the blade.

3. Means for attaching and removing detachable blades from a blade holder, including a wooden base, an upwardly projecting metal member secured to said base, and a longitudinal slot in said member in which the blade may be inserted, one end of said slot being under-cut to engage the pointed end of said blade and the other end of said slot adapted to act as a stop, whereby the blade will be held while said holder is longitudinally moved into or withdrawn from holding engagement with the blade. 40

4. Means for attaching and removing detachable blades from a blade holder, including a wooden base, a sheet metal member having a longitudinal slot in the top thereof into which said blade may be inserted so as to be held longitudinally by the ends thereof while the holder is withdrawn therefrom, and longitudinal flanges on each side of said member for securing it to the base. 45

In witness whereof, I have hereunto affixed my signature.

ARTHUR R. BARNETT.
